TRADE STAMP DISPENSER

Joe Beard, 7813 N. New Braunfels, San Antonio, Tex.

Filed July 2, 1959, Ser. No. 824,692

9 Claims. (Cl. 225—33)

This invention relates to improvements in dispensing containers for sheet material, and more particularly to a dispenser for trading stamps.

The primary object of the invention is to provide a more efficient, and practical device of this kind which enables an accurate dispensing of predetermined numbers of trading stamps, in a single sheet, rather than in separate strips, whereby the dispensing can be performed more quickly and easily by a merchant, with greater satisfaction and convenience to customers.

Another object of the invention is to provide a compact, portable, rugged, and easily operated device of the character indicated above, which is of uncomplicated construction, being composed of a small number of simple parts, and being capable of being made in attractive and serviceable forms at relatively low cost, of such readily available and suitable materials as plastics and lightweight metals.

Other important objects and advantageous features of the invention will be apparent from the following description and accompanying drawings, wherein, for purposes of illustration only, a specific form of the invention is set forth in detail.

In the drawings:

Figure 1 is a perspective view of a device of the invention, a roll of trading stamps being shown in phantom lines in position in the device;

Figure 2 is an enlarged vertical longitudinal section taken on the line 2—2 of Figure 1; and

Figure 3 is a vertical transverse section taken on the line 3—3 of Figure 2.

Referring in detail to the drawings, wherein like numerals designate like parts through the several views, the illustrated device, generally designated 10, comprises a longitudinally elongated base 12, which has a horizontal longitudinal trading stamp supporting surface 14, at whose rear end is a depressed semi-cylindrical well 16 for a roll R of trading stamps. The base 12 is preferably of inverted channel cross section, having parallel side walls 18 to and between which a plate or top wall 20 is fixed, whose upper side provides the supporting surface 14. From an intermediate length point to the rear end of the base 12, the side walls 18 have vertical longitudinal extensions 22, which rise above the top wall 20. The well 16 can be a continuation of the top wall 20 at the rear end thereof.

Extending between and fixed to the side wall extensions 22, at a point near to the end of the top wall 20, and at the forward end of the top wall, are similar rear and forward cross bars 24 and 26, respectively, which are spaced upwardly from the surface 14. Also extending between and suitably fixed to the side wall extensions is a smooth, preferably plastic separator plate 28, which extends the length of the side wall extensions 22, between the well 16 and the forward ends of the extensions. The plate 28 is spaced below the undersides of the cross bars 24 and 26 and spaced upwardly from the surface 14.

2

The plate 28 provides between itself and the surface 14 a horizontal slot 30 through which a trading stamp strip 32 is drawn forwardly from a roll R resting in the well 16. The plate 28 also serves as the slide base for slidably supporting a plurality of cutter slides 34, which are disposed longitudinally, and in side-by-side positions, beneath the cross bars 24 and 26 and the plate 28, and between the side wall extensions 22.

While the structure described above can be made of any suitable materials, transparent plastic is preferred, as being light-weight, sturdy, non-rusting and non-corrosive, pleasant to the touch, and as providing desirable transparency affording visual checking of trading stamps beneath the cutter slides 34. Further, heavy gauge plastic construction gives the right weight and handle for use of the device on such as a market checking-out counter or the like.

The cutter slides 34 are similar in construction, and five in number for use with a stamp strip 32 containing five longitudinal rows 36 of stamps 38, separated by longitudinal perforations 39, with stamps arranged in transverse rows 40 for five stamps each, separated by transverse perforations 41. Each cutter slide 34 comprises a longitudinally elongated flat bar 42 of substantial cross section, on whose top side are fixed rear and forward stop blocks 44 and 46, respectively, which serve also as handles for sliding the slides 34. The rear block 44 is located on the slide bar 42 to have stop engagement with the forward edge of the rear cross bar 24, when in a retracted cutting position of the slide; and the forward block 46 is located on the bar 42 to have stop engagement with the rear edge of the forward cross bar 26 in a forward position of the slide 34. The slide bars 42 are longer than the distance between the rear edge of the rear cross bar 24 and the forward edge of the forward cross bar 26, so that a forward end portion 48 of the slide bar 42, slightly longer than a trading stamp, can extend forwardly beyond the forward cross bar 26 when the forward stop block 46 is engaged with the forward cross bar. The rear block 44 is located on the slide bar 42 so that when it is engaged with the rear cross bar 24, the forward end portion 48 is partially retracted under the forward cross bar 26, as seen in the upper part of Figure 1, so that the forward cutting edge 50 of the retracted cutter slide is spaced rearwardly from the cutting edge 50 of the unretracted slides, at a distance equal to the length of one stamp.

The cutting edges 50 of the slides 34 are defined by downward bevels 52 on the forward ends of the slide bars 42, extending down to the undersurfaces 54 of the slide bars, and downward bevels 56 on the forward ends of short transversely elongated bearing plates 58, preferably of plastic, suitably secured to the undersurfaces 54, and slidably bearing upon the supporting surface, the bevels 52 and 56 being flush and continuous with each other. The bearing plates 58 are of the same thickness as the separator plate 28.

In use of the device 10, the stamp strip 32 having been passed forwardly through the slot 30 so as to extend forwardly beyond the cutting edges 50 of the slides 34, at least as far as to put a transverse perforation 41 in line with the cutting edge of a retracted slide 34, as shown in the upper part of Figure 1, at the side of the device away from the operator thereof, all of the stamps 38 forwardly of the retracted slide, or the single stamp in front of the retracted slide, can be torn off the strip 32 by pulling the same upwardly and along the cutting edges. The slides 34 can be selectively and individually retracted and extended, so as to position their cutting edges 50 correctly for tearing off, in one sheet, any desired number of stamps 38 from the strip 32, in accordance with the

arrangement of stamps existing in the exposed part of the strip 32, resulting from preceding dispensings of stamps. Because the exposed part of the strip 32 lying upon the supporting surface 14 is readily seen by both merchant and customer, both can at once determine the number of stamps 38 so exposed, both before, and in process of tearing the correct number of stamps from the strip 32, so that controversies over the correct dispensing of stamps cannot readily arise.

It will be understood that the herein described device is especially usable for dispensing other than trading stamps, from rolls of similarly arranged strips.

Although there has been shown and described herein a preferred form of the invention, it is to be understood that the invention is not necessarily confined thereto, and that any change or changes in the structure of and in the relative arrangements of components thereof are contemplated as being within the scope of the invention as defined by the claims appended hereto.

What is claimed is:

1. A trading stamp dispenser comprising an elongated horizontal base having a horizontal supporting surface having rear and forward ends, a stamp roll holding well on the base at one end of said surface, a horizontal separator plate on the base and extending along and spaced above said surface and with said surface defining a slot through which a strip can be drawn along said surface from a roll in the well, a plurality of longitudinal slides bearing slidably upon said separator plate, said slides being in side-by-side relation to each other and being individually movable rearwardly to retracted positions and forwardly to extended positions, means on the base confining said slides in position in the separator plate, and cutting edges on the forward ends of the slides.

2. A trading stamp dispenser comprising an elongated horizontal base having a horizontal supporting surface having rear and forward ends, a stamp roll holding well on the base at one end of said surface, a horizontal separator plate on the base and extending along and spaced above said surface and with said surface defining a slot through which a strip can be drawn along said surface from a roll in the wall, a plurality of longitudinal slides bearing slidably upon said separator plate, said slides being in side-by-side relation to each other and being individually movable rearwardly to retracted positions and forwardly to extended positions, means on the base confining said slides in position in the separator plate, and cutting edges on the forward ends of the slides, said supporting surface reaching forwardly beyond the cutting edges of extended slides for supporting an uncut portion of a stamp strip thereon.

3. A trading stamp dispenser comprising an elongated horizontal base having a horizontal supporting surface having rear and forward ends, a stamp roll holding well on the base at one end of said surface, a horizontal separator plate on the base and extending along and spaced above said surface and with said surface defining a slot through which a strip can be drawn along said surface from a roll in the well, a plurality of longitudinal slides bearing slidably upon said separator plate, said slides being in side-by-side relation to each other and being individually movable rearwardly to retracted positions and forwardly to extended positions, means on the base confining said slides in position in the separator plate, and cutting edges on the forward ends of the slides, said supporting surface reaching forwardly beyond the cutting edges of extended slides for supporting an uncut portion of a stamp strip thereon, said confining means comprising longitudinal side wall extensions located in the base along the opposite sides of and rising above said separator plate, and longitudinally spaced rear and forward cross bars fixed to and extending between the extensions and spaced above the separator plate, said slides com-

prising slide bars positioned between the separator plate and the cross bars.

4. A trading stamp dispenser comprising an elongated horizontal base having a horizontal supporting surface having rear and forward ends, a stamp roll holding well on the base at one end of said surface, a horizontal separator plate on the base and extending along and spaced above said surface and with said surface defining a slot through which a strip can be drawn along said surface from a roll in the well, a plurality of longitudinal slides bearing slidably upon said separator plate, said slides being in side-by-side relation to each other and being individually movable rearwardly to retracted positions and forwardly to extended positions, means on the base confining said slides in position in the separator plate, and cutting edges on the forward ends of the slides, said supporting surface reaching forwardly beyond the cutting edges of extended slides for supporting an uncut portion of a stamp strip thereon, said confining means comprising longitudinal side wall extensions located in the base along the opposite sides of and rising above said separator plate, and longitudinally spaced rear and forward cross bars fixed to and extending between the extensions and spaced above the separator plate, said slides comprising slide bars positioned between the separator plate and the cross bars, said slide bars having inwardly of the forward ends upstanding rear and forward stop blocks fixed thereon and located between and engageable at times with the cross bars.

30 5. A trading stamp dispenser comprising an elongated horizontal base having a horizontal supporting surface having rear and forward ends, a stamp roll holding well on the base at one end of said surface, a horizontal separator plate on the base and extending along and spaced above said surface and with said surface defining a slot through which a strip can be drawn along said surface from a roll in the well, a plurality of longitudinal slides bearing slidably upon said separator plate, said slides being in side-by-side relation to each other and being individually movable rearwardly to retracted positions and forwardly to extended positions, means on the base confining said slides in position in the separator plate, and cutting edges on the forward ends of the slides, said supporting surface reaching forwardly beyond the cutting edges of extended slides for supporting an uncut portion of a stamp strip thereon, said confining means comprising longitudinal side wall extensions located in the base along the opposite sides of and rising above said separator plate, and longitudinally spaced rear and forward cross bars fixed to and extending between the extensions and spaced above the separator plate, said slides comprising slide bars positioned between the separator plate and the cross bars, said slide bars having inwardly of the forward ends upstanding rear and forward stop blocks fixed thereon and located between and engageable at times with the cross bars, the rear stop blocks being located to have stop engagement with the rear cross bar in retracted positions of the slides and said forward stop blocks being located in the slide bars to have stop engagement with the forward cross bar in the extended positions of the slides, said forward end portions of the slide bars being proportioned in length to locate the cutting edges of retracted slides behind the cutting edges of extended slides at a distance equal to the length of a stamp of the strip.

60 6. A trading stamp dispenser comprising an elongated horizontal base having a horizontal supporting surface having rear and forward ends, a stamp roll holding well on the base at one end of said surface, a horizontal separator plate on the base and extending along and spaced above said surface and with said surface defining a slot through which a strip can be drawn along said surface from a roll in the well, a plurality of longitudinal slides bearing slidably upon said separator plate, said slides being in side-by-side relation to each other and

70

75

being individually movable rearwardly to retracted positions and forwardly to extended positions, means on the base confining said slides in position in the separator plate, and cutting edges on the forward ends of the slides, said supporting surface reaching forwardly beyond the cutting edges of extended slides for supporting an uncut portion of a stamp strip thereon, said confining means comprising longitudinal side wall extensions located in the base along the opposite sides of and rising above said separator plate, and longitudinally spaced rear and forward cross bars fixed to and extending between the extensions and spaced above the separator plate, said slides comprising slide bars positioned between the separator plate and the cross bars, said slide bars having inwardly of the forward ends upstanding rear and forward stop blocks fixed thereon and located between and engageable at times with the cross bars, the rear stop blocks being located to have stop engagement with the rear cross bar in retracted positions of the slides and said forward stop blocks being located in the slide bars to have stop engagement with the forward cross bar in the extended positions of the slides, said forward end portions of the slide bars being proportioned in length to locate the cutting edges of retracted slides behind the cutting edges of extended slides at a distance equal to the length of a stamp of the strip, said forward end portions having bearing plates affixed to their undersides of the same thickness as the separator plate and bearing upon said supporting surface.

7. A trading stamp dispenser comprising an elongated horizontal base having a horizontal supporting surface having rear and forward ends, a stamp roll holding well on the base at one end of said surface, a horizontal separator plate on the base and extending along and spaced above said surface and with said surface defining a slot through which a strip can be drawn along said surface from a roll in the well, a plurality of longitudinal slides bearing slidably upon said separator plate, said slides being in side-by-side relation to each other and being individually movable rearwardly to retracted positions and forwardly to extended positions, means on the base confining said slides in position in the separator plate, and cutting edges on the forward ends of the slides, said supporting surface reaching forwardly beyond the cutting edges of extended slides for supporting an uncut portion of a stamp strip thereon, said confining means comprising longitudinal side wall extensions located in the base along the opposite sides of and rising above said separator plate, and longitudinally spaced rear and forward cross bars fixed to and extending between the extensions and spaced above the separator plate, said slides comprising slide bars positioned between the separator plate and the cross bars, said slide bars having inwardly of the forward ends upstanding rear and forward stop blocks fixed thereon and located between and engageable at times with the cross bars, the rear stop blocks being located to have stop engagement with the rear cross bar in retracted positions of the slides and said forward stop blocks being located in the slide bars to have stop engagement with the forward cross bar in the extended positions of the slides, said forward end portions of the slide bars being proportioned in length to locate the cutting edges of retracted slides behind the cutting edges of extended slides at a distance equal to the length of a stamp of the strip, said forward end portions having bearing plates affixed to their undersides of the same thickness as the separator plate and

bearing upon said supporting surface, the forward ends of the slide bars and bearing plates being downwardly bevelled to the undersides of the bearing plates to define said cutting edges.

- 5 8. A trading stamp dispenser comprising an elongated
horizontal base having a horizontal supporting surface
having rear and forward ends, a stamp roll holding well
on the base at one end of said surface, a horizontal
separator plate on the base and extending along and
spaced above said surface and with said surface defining
10 a slot through which a strip can be drawn along
said surface from a roll in the well, a plurality of longitudinal
slides bearing slidably upon said separator plate,
said slides being in side-by-side relation to each other
15 and being individually movable rearwardly to retracted
positions and forwardly to extended positions, means on
the base confining said slides in position in the separator
plate, and cutting edges on the forward ends of the slides,
said supporting surface reaching forwardly beyond the
20 cutting edges of extended slides for supporting an uncut
portion of a stamp strip thereon, said confining means
comprising longitudinal side wall extensions located in
the base along the opposite sides of and rising above said
separator plate, and longitudinally spaced rear and for-
25 ward cross bars fixed to and extending between the ex-
tensions and spaced above the separator plate, said slides
comprising slide bars positioned between the separator
plate and the cross bars, said base being hollow and
comprising spaced side walls having lower edges to rest
30 upon a support, and upper edges, said side wall exten-
sions being on the upper edges of the side walls and be-
ing spaced at their forward ends from the forward end of
the supporting surface.

9. A trading stamp dispenser comprising an elongated
35 horizontal base having a horizontal supporting surface
having rear and forward ends, a stamp roll holding well
on the base at one end of said surface, a horizontal
separator plate on the base and extending along and
spaced above said surface and with said surface defining
40 a slot through which a strip can be drawn along said
surface from a roll in the well, a plurality of longitudinal
slides bearing slidably upon said separator plate, said slides
being in side-by-side relation to each other and
being individually movable rearwardly to retracted pos-
45 tions and forwardly to extended positions, means on the
base confining said slides in position in the separator
plate, and cutting edges on the forward ends of the slides,
said supporting surface reaching forwardly beyond the
50 cutting edges of extended slides for supporting an uncut
portion of a stamp strip thereon, said confining means
comprising longitudinal side wall extensions located in
the base along the opposite sides of and rising above
said separator plate, and longitudinally spaced rear end
55 forward cross bars fixed to and extending between the
extensions and spaced above the separator plate, said slides
comprising slide bars positioned between the separator
plate and the cross bars, said base being hollow and
comprising spaced side walls having lower edges to rest
60 upon a support, and upper edges, said side wall exten-
sions being on the upper edges of the side walls and
being spaced at their forward ends from the forward
end of the supporting surface, said well being a semi-
cylindrical continuation of said top wall at the rear end
65 of the supporting surface.
